TILE DRAIN PLUG

Edward J. Lause, Milton Road,
Custar, Ohio 43511

Filed Apr. 29, 1969, Ser. No. 16,934

Term of patent 14 years

Int. Cl. D23—01

U.S. Cl. D23—42

FIG-1-

FIG-2-

FIG-3-

FIG-4-

FIGURE 1 is a top or end view of the tile drain plug of my new design:

FIGURE 2 is a view in elevation;

FIGURE 3 is a cross-sectional view in elevation taken along line 3—3 of FIGURE 1.

FIGURE 4 is a bottom view.

I claim:

The ornamental design for a tile drain plug, as shown and described.
